CLAIM

I claim the ornamental design for a display board, as shown and described.

DESCRIPTION

FIG. 1 is a front perspective view of a display board of the present invention.

FIG. 2 is a front view of the display board of FIG. 1.

FIG. 3 is a top view of the display board of FIG. 1.

FIG. 4 is a bottom view of the display board of FIG. 1.

FIG. 5 is a left-side view of the display board of FIG. 1.

FIG. 6 is a right-side view of the display board of FIG. 1; and, FIG. 7 is a rear view of the display board of FIG. 1.

The broken lines showing features on the bottom and rear of the display board are included for the purpose of illustrating environment and form no part of the claimed design.

The stippling shown on the display board in FIGS. 1, 2, and 5 represents a contrast of materials.
